Application September 3, 1935, Serial No. 39,042
 In France December 29, 1934

2 Claims. (Cl. 175—356)

The present invention relates to electric transformers, and chiefly to transformers which are used for high tension.

Hitherto, the construction of such apparatus has been attended with difficulties concerning the insulation of the windings from one another or from ground. These difficulties are due to the lack of symmetry of the parts to be insulated, thus making it necessary to give complicated forms to the insulating members, to the detriment of their dielectric properties. Various methods have been considered, up to the present, for obviating this drawback. The dimensions of the magnetic circuit have been increased in order to remove the windings from the unsymmetrical parts of this latter. Use has also been made of a dielectric such as oil, which readily penetrates between the parts to be insulated and at once adapts itself to the most complex forms. However, the first method leads to the use of very bulky and heavy apparatus which is not convenient, while the use of oil does not lead to any great reduction of the size, and it is always, with the great volume necessary, a source of serious danger from fire.

The present invention has for its object the construction of a transformer which does not offer these drawbacks. It is proposed to utilize for this purpose, instead of the closed magnetic circuit which is in general use, an open magnetic circuit, which is symmetrical with reference to an axis. This magnetic circuit carries windings separated by a condenser type insulating sleeve having metallic facings which are connected to different points of the windings. The dielectric of the condenser further assures the insulation of the windings from ground.

The invention will be better understood with reference to the accompanying drawing.

Figure 1 shows a constructional form of transformer of the high-tension type.

Figure 2 is a diagram of the arrangement of the transformer.

Figure 3 shows the arrangement of the plates forming the laminated core of the transformer.

Figure 4 represents the application of the insulation according to the invention to the end of the cable supplying the transformer.

The apparatus shown in Figure 1 is a high-tension transformer having one terminal connected to ground. The open magnetic circuit A is straight, and has a cylindrical form. As the reluctance of this circuit is very high, an enlarged part B is provided at the base in order to reduce the reluctance, but the top part can-

not comprise a like enlargement, owing to difficulties in the insulation.

Immediately around this magnetic circuit is the low-tension winding C, which is insulated from the high-tension winding E by an insulating sleeve member D having an inverted conical outer surface arranged coaxially with the magnetic circuit. The inner surface of the high-tension winding also has the form of a hollow inverted cone coaxial with the magnetic circuit. 10

The insulating member D consists of a condenser comprising cylindrical metallic facing parts M, M, which have a parallel position, each being connected at the lower end to a different point N, N of the high-tension winding E, in 15 order to distribute the differences of potential of the high-tension winding in the insulating member.

The purpose of this insulating member provided with the facing parts will be better understood 20 with reference to Figure 2. In fact, the use of condensers connected as shown in Figure 2, has for its object, on the one hand, to compensate the increase of current at no load which is due to the open magnetic circuit, as the reduction of 25 this current is advantageous, and on the other hand, to facilitate the distribution, upon the winding, of surges which may come from the exterior, such as may be caused by lightning, or the like.

The core A consists of radial plates arranged in groups, as shown in Figure 3, which represents a cross-section of the magnetic circuit, in order to reduce the loss in the iron due to eddy currents.

It will thus be observed that the construction of 35 this transformer offers numerous advantages, due to the combination of a straight open magnetic circuit, with an insulating member provided with metallic facing parts, providing units of a condenser.

In fact, the use of a straight magnetic circuit facilitates the insulation of the high-tension winding, by giving to the dielectric a very simple form, that of a circular tube, without making it necessary to increase the dimensions of the 45 parts of the apparatus. Thus a solid dielectric can be used, while at the same time obtaining perfect insulation.

Should it be advantageous to use oil, in order to facilitate the cooling, for example, the transformer may be placed in a cylindrical tank of insulating material, the diameter of which is only slightly greater than that of the windings, and this will only require an extremely small amount of oil.

This arrangement is particularly advantageous in a high-tension transformer, as its general size is proportional to the tension, whereas in apparatus with closed magnetic circuit employing oil, the size will vary about as the cube of the tension.

The progressive distribution of the differences of potential in the high-tension winding may be extended to adjacent apparatus. It is particularly applicable to the distribution of the tension upon the terminal end of a cable P serving to supply the transformer, and for this purpose it is simply necessary to carry out the arrangement shown in Figure 4, which represents the possible connections between the facing parts d which are mounted on the cable, and the winding E of the transformer.

The characteristics of this apparatus, as a measuring transformer, are as follows:

- 20 1. Its no-load current is small.
2. Its accuracy is considerable.

In fact, the value of the current at no load is favorably affected: (a) by the enlargement of the lower part of the magnetic circuit; (b) by 25 the arrangement of the plates of the core, as shown in Figure 3; (c) by the use of condensers connected as shown in Figure 2.

It is shown in the preceding considerations that on the one hand, this apparatus possesses, 30 in addition to its own advantages, many of those of transformers with closed magnetic circuits and has few of the disadvantages of transformers with open magnetic circuit, in which the degree of accuracy can only be a very small fraction 35 of the apparent power absorbed at no load, as such apparatus has either a very low degree of accuracy or a very large current at no load.

I claim:

1. In an electrical high tension support type 40 transformer, an open magnetic circuit iron core having a bar-like vertical portion and a support-

ing base portion adapted to be grounded, a low voltage winding arranged along the bar-like portion of the core, a high voltage winding having a generally conically shaped interior surface arranged over the low voltage winding, a plurality of insulated metal cylinders in stepped coaxial arrangement between the high and low voltage windings to provide capacity elements of a condenser, the inner cylinders being of greater length than the outer cylinders to substantially fill the space between the two windings, the area of the outermost cylinder equaling at least one-half of the area of the innermost cylinder, and all of said cylinders extending beyond the two windings at the upper end thereof and the outer cylinders projecting beyond the upper end of said core.

2. In an electrical high tension support type transformer, an open magnetic circuit iron core having a bar-like vertical portion and an enlarged supporting base portion adapted to be grounded, a low voltage winding arranged along the bar-like portion of the core, a high voltage winding having a generally conically shaped interior surface arranged over the low voltage winding, a plurality of insulated metal cylinders in stepped coaxial arrangement between the high and low voltage windings to provide capacity elements of a condenser, the inner cylinders being of greater length than the outer cylinders to substantially fill the space between the two windings, the area of the outermost cylinder equaling at least one-half the area of the innermost cylinder, all of said cylinders extending beyond the two windings at the upper end thereof and the outer cylinders projecting beyond the upper end of said core, and the successive outer cylinders projecting beyond each preceding inner cylinder.
